UNITED STATES PATENT OFFICE.

FLOYD A. FERRIS, OF DALLAS, TEXAS.

ORDER-FILLING COUNTER.

1,421,679.

Specification of Letters Patent. Patented July 4, 1922.

Application filed August 26, 1921. Serial No. 495,574.

To all whom it may concern:

Be it known that I, FLOYD A. FERRIS, a citizen of the United States, residing at Dallas, in the county of Dallas and State of Texas, have invented certain new and useful Improvements in Order-Filling Counters, of which the following is a specification.

This invention relates to new and useful improvements in order filling counters.

10 In preparing orders for merchandise consisting of numerous articles, it is customary in mercantile establishments to collect the various articles and deliver the same to a clerk who packs them for shipment. It is necessary to segregate the articles of one order from those of another, and as considerable delay is sometimes had in completing the order, owing to difficulty in procuring or locating one or more articles, confusion 15 and displacement of the articles of the various orders often results while the same are being held on the packers' table awaiting completion. It is necessary to check and re-check the orders to see that each is complete, and even after this is done, articles of one order frequently get mixed with those of another.

The object of my invention is to provide means for positively and accurately segregating the articles of one order from those of others, and to preclude the possibility of the articles of the various orders becoming mixed. A further object of the invention is to provide a separate compartment for 35 each order, arranged in such a manner as to adequately separate its articles from those of other orders.

Another object of the invention is to provide means whereby the packing clerk is 40 informed when the order is complete and ready for packing, so that he need not waste time in checking over orders for ascertaining whether they are ready for packing. Another object of the invention is to provide 45 means for informing the shipping clerk that the order has been filled and is ready to be shipped by him.

In carrying out the invention a plurality of compartments are arranged so that each 50 is adequately separated from the others. Each compartment is provided with closures on opposite sides, connected so that when one is open the other is closed and vice versa.

55 A construction designed to carry out the invention will be hereinafter described to-

gether with other features of the invention.

The invention will be more readily understood from a reading of the following specification and by reference to the accompanying drawings, in which an example of the invention is shown, and wherein:

Fig. 1 is an elevation showing the order filler's side of a plurality of compartments constructed in accordance with my 60 invention.

Fig. 2 is a plan view of the same.

Fig. 3 is a detail showing one of the pulleys.

Fig. 4 is an enlarged vertical sectional 70 view on the line 4—4 of Fig. 1, and

Fig. 5 is an enlarged horizontal cross-sectional view on the line 5—5 of Fig. 1.

In the drawings the numeral 10 designates a counter or other support forming the base 75 for the compartments, which should be set at a convenient height for those working with the same. On top of the counter or a support 10 I form a plurality of compartments or bins 11.

It is to be understood that the bins may be formed in any suitable manner, but I have found a satisfactory construction to be as described and illustrated herein, however the invention is not to be limited to the 85

same. Along each side I mount a flat top rail 12. The rails are supported on each side of the structure by uprights 13, each of which has a vertical facing strip 14 at its front edge. Each facing strip is wide 90 enough to overlap the upright and, co-acting with a vertical guide strip 14' disposed inwardly of the upright, forms a guideway 15. The guideways 15 on one side of the structure receive sashes 16 and each pair 95 of guideways on the other side receive a sash 17. Centrally over each sash a pulley 18 is mounted in a slot 19 as is illustrated in detail in Fig. 3. The sashes on opposite sides are connected by a flexible cable 100 or other connection 20, which passes over the pulleys and is attached to the top end of the sashes. The cable 20 in each instance is of such length as to hold one sash 16 elevated while the opposite sash 17 is at its 105 normal position, and whereby when the sash 16 is pulled down the sash 17 will be elevated.

I prefer to mount in each sash a panel 21 of wire fabric or other material. This particular material has the advantage of being 110 of light weight and unobstructive to light.

The compartments are separated by cross-partitions which extend between the uprights 13 and comprise a bottom bar 22 connected with a top bar 23 by a panel 24 of wire fabric or other material. It is to be understood, however, that the partitions may be made of any suitable material.

I have shown compartments of different widths and the order filler may select the compartment to be used in accordance with the size of the order to be filled. The compartment may be the width of the sash, as is shown in Fig. 1, or the compartment may be widened by employing a panel 25 between two of the uprights, as is illustrated in Fig.

1. It is to be understood that various modifications of this nature may be made without departing from the spirit of the invention. At the top of each sash a suitable clip or holder 26 is provided which may be employed to secure the sheets of paper on which the order is written. This is not an essential feature but can be used to advantage. The compartments immediately above the sashes are shown to be open, when the sash is lowered, but it is within the scope of the invention to cover the same.

In using the counter the sashes 16 are raised whereby the sashes 17 are lowered. The sashes 17 are on the packer's aisle and as long as they remained closed the packer is informed that the orders are not ready to be packed. The order clerks place the articles comprising the various orders in the different compartments 11, a separate compartment being selected for each order. When an order has been filled the order clerk attaches the order by the clip 26 and goes about his work. The shipping clerk sees the order sheet held by the clip, and is thus informed that the order is filled and ready for checking. The shipping clerk checks the order, signs the same, and then pulls down the sash 16. When the sash 16 is pulled down, the sash 17 is raised and the packer is, therefore, notified immediately

that the order is ready to be packed. This makes a great saving of time and the packer does not have to bother with any compartment until the sash 17 is raised. The order clerk does not have to wait for the shipping clerk to check the order and the shipping clerk does not have to wait for the order clerk to fill the order. By this system there is no chance for the articles of one order becoming mixed with those of another order, as the packer packs only the articles from one order at a time. If the order clerk places the articles in the proper bin, there can be no mistakes.

What I claim, is:

1. In a device of the character described, an elongated counter, uprights mounted on each side of the counter, transverse partitions extending from the uprights on one side of the counter to uprights on the opposite side of the counter, sashes slidably between the uprights, pulleys disposed between the upper ends of the uprights, and flexible connections extending from the sashes on one side over the pulleys to the sashes on the other side.

2. An order filling counter comprising, a working counter being accessible from its opposite sides, a plurality of separate transverse compartments formed upon the working counter and having their sides open and accessible from the opposite sides of the counter, a pair of sashes vertically slidably mounted within the openings upon the opposite sides of each compartment and adapted to cover and uncover said openings, guide means supported above such openings, and a cable engaging the guide means and connected with the sashes in each pair in a manner whereby the weight of one sash is employed to counterbalance the other sash, and when one sash is in the lowermost position the other sash is in the uppermost position.

In testimony whereof I affix my signature.

FLOYD A. FERRIS.
